US00D690739S

(12) **United States Design Patent**
Akana et al.

(10) **Patent No.:** US D690,739 S
(45) **Date of Patent:** ** Oct. 1, 2013

(54) **ELECTRONIC DEVICE**

- (71) Applicant: **Apple Inc.**, Cupertino, CA (US)
- (72) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)
- (73) Assignee: **Apple Inc.**, Cupertino, CA (US)
- (**) Term: **14 Years**
- (21) Appl. No.: **29/449,810**
- (22) Filed: **Mar. 15, 2013**

Related U.S. Application Data

- (63) Continuation of application No. 29/428,517, filed on Jul. 31, 2012, now Pat. No. Des. 678,336, which is a continuation of application No. 29/413,693, filed on Feb. 17, 2012, now Pat. No. Des. 664,995, which is a continuation of application No. 29/391,989, filed on May 16, 2011, now Pat. No. Des. 654,506, which is a continuation of application No. 29/367,996, filed on Aug. 16, 2010, now Pat. No. Des. 638,030.

(57) **CLAIM**

The ornamental design for an electronic device, as shown and described.

DESCRIPTION

FIG. 1 is a front bottom perspective view of an electronic device showing our new design;

FIG. 2 is a rear bottom perspective view thereof;

FIG. 3 is a rear top perspective view thereof;

FIG. 4 is a front top perspective view thereof;

FIG. 5 is a front view thereof;

FIG. 6 is a rear view thereof;

FIG. 7 is a bottom view thereof;

FIG. 8 is a top view thereof;

FIG. 9 is a side view thereof; and,

FIG. 10 is another side view thereof.

1 Claim, 8 Drawing Sheets
